UNITED STATES PATENT OFFICE

2,642,175

PORTABLE CONVEYER

Thomas Ryan Mahoney, Greenville, Ohio, assignor, by mesne assignments, to The Chase Foundry & Manufacturing Company, Columbus, Ohio

Application January 30, 1950, Serial No. 141,249

2 Claims. (Cl. 198—121)

1

This invention relates to a portable conveyor. An object of this invention is to provide a portable elevator for use in elevating grain or other material, the elevator including collapsible props so that the elevator may be lowered to a substantially horizontal collapsed position whereby the elevator may be moved from one location to another.

Another object of this invention is to provide in a grain lift or elevator, an improved conveyor wherein the wear between the conveyor and frame have been greatly reduced, and the noise of the conveyor chains has been materially reduced.

A further object of this invention is to provide a grain lift or elevator including screen means in the elevator structure for screening out loose material.

A further object of this invention is to provide a grain lift or elevator including an improved means for raising and lowering the elevator, the means including a worm and worm gear so that the elevator will be locked in any selected adjustment thereof.

With the above and other objects in view, my invention consists in the arrangement, combination and details of construction disclosed in the drawings and specification, and then more particularly pointed out in the appended claims.

In the drawings:

Figure 1 is a detailed side elevation of a portable elevator constructed according to an embodiment of this invention showing the elevator in extended operative position.

Figure 2 is a transverse sectional view taken on the line 2—2 of Figure 1.

Figure 3 is a fragmentary plan view of the rear end of the elevator showing the driving means for the conveyor.

Figure 4 is a detailed side elevation partly broken away of the rear end of the elevator.

Figure 5 is a fragmentary sectional view through the worm for the winding drum.

Figure 6 is a fragmentary plan view of one of the chains.

Figure 7 is a fragmentary side elevation of one of the conveyor chains.

Figure 8 is a fragmentary plan view taken in the zone indicated by the lines 8—8 of Figure 1.

Figure 9 is a fragmentary sectional view taken on the line 9—9 of Figure 8.

Figure 10 is a fragmentary sectional view taken on the line 10—10 of Figure 8.

Referring to the drawings, the numeral 15 designates generally an elongated frame structure which is formed of upper angle members 16

2

and lower angle members 17 which are connected to the upper angle members 16 by means of a plurality of spaced apart connecting bars 18. A plurality of bottom bars 19 are fixedly secured at spaced intervals between the lower angle members 17.

An elongated trough generally designated as 20 is disposed lengthwise of the frame 15 and includes a bottom plate 21 having secured to the opposite lengthwise edges thereof flanges 22, and the flanges 22 have extending right angularly and upwardly therefrom side walls 23. The side walls 23 terminate at their upper edges in outwardly projecting flanges 24 which are secured by fastening means 25 to the upper angle members 16.

The bottom member 21 of the trough 20 has fixed to the opposite lengthwise edges thereof a pair of non-metallic runners 26 which are secured to the bottom 21 by fastening members 27.

20 A conveyor generally designated as 28 is movably disposed within the frame 15 and comprises a pair of endless chains 29 having their upper runs engaging over the runners 26. A plurality of transversely extending cleats 30 are secured 25 between the runs of the chains 29 being secured to the chains 29 by means of triangular lugs 31 which are secured to spaced links of the chains 29. The chains 29 are trained over a pair of driving sprockets 32 which are secured to a shaft 33 journaled in bearings 34 carried by the frame 15 adjacent the rear of the frame. The chains 29 are also trained over idler sprockets 35 carried by an idler shaft 36 which is journaled in a pair of adjustable bearing blocks 37 carried by the forward end of the frame 15.

35 The shaft 33 has fixed thereto a relatively large sprocket 38 about which a chain 39 engages, and the chain 39 engages about a relatively small sprocket 40 which is carried by an intermediate or jack shaft 41 journaled in bearings 42 carried by the frame 15. The shaft 41 has fixed thereto a relatively large pulley 43 about which more endless belts 44 engage, and the belts 44 engage about driving pulleys 45 carried by a power shaft 46. The shaft 46 is rotated by a power member 47 which may be an electric motor or an internal combustion engine. The trough 20 is formed between the ends thereof with an opening 48, and a grill or screening member 49 engages beneath the opening 48 and is adapted to screen out any loose material which is moved along the bottom of the trough 20.

50 The screen or grill 49 is formed of a plurality of parallel lengthwise extending bars 50 which are secured to a looped frame 51, and the rear

and forward ends of the frame 51 are secured to transversely extending bars 52 which are secured by fastening means 53 to the bottom 21 of the trough.

A mobile frame 54 is disposed below the frame 15 being provided with a pair of wheels 55, and the frame 54 is connected to the rear portion of the frame 15 by means of elongated links 56. The links 56 are pivotally connected between the frame 15 and the frame 54, the purpose for which will be hereinafter described.

A second pair of elongated links 57 are pivotally connected at their inner ends to the frame 54 and are provided at their outer ends with rollers 58 which movably engage beneath the frame 15. The links 57 are adapted to be locked relative to the frame 54 so as to either extend or retract the frame 15 by means of a flexible member 59 which is trained over a pulley 60 carried by the outer portions of the links 57. The flexible member 59 is secured at one end to the sheave frame 61 and is then trained about an intermediate pulley 62 carried by the frame 15 forwardly of the pivotal connection of the links 58 with the frame 15. The flexible member 59 is extended rearwardly and is wound about a winding drum 63 which is carried by a shaft 64 journalled across the frame 15.

A worm gear 65 is fixed to the shaft 64, and the gear 65 has meshing therewith a worm 66 which is slidable but non-rotatable on a shaft 67. The shaft 67 is journalled at one side of the frame 15 lengthwise of this frame in bearings 68 and 69.

A spring 70 is disposed about the shaft 67 bearing at one end against one end of the worm 66 and bearing at its other or rear end against a collar 71 which is fixed on the shaft 67. The shaft 67 is rotated by means of a bevel gear 72 which is fixed on the shaft 41, and gear 72 is adapted to mesh with a selected one of a pair of gears 73 and 74. The gears 73 and 74 are fixed on the shaft 67 being held in spaced apart relation by means of a sleeve 75 engaging about the shaft 67. A selected one of the gears 73 or 74 is moved into mesh with the gear 72 by means of a shifting fork 76 pivotally carried by a supporting bar 77 and engaging between a pair of collars 78 which are secured to the shaft 67. The shifting fork 76 includes an elongated lever 79 having a spring pressed pawl 80 which is adapted to engage in a notch 81 carried by an arcuate keeper bar 82. The dog or pawl 80 when engaged in the keeper notch 81 is adapted to hold the gears 73 and 74 in neutral or disengaged position with respect to gear 72.

In the use and operation of this elevator, the rear end of the elevator may be coupled to a tractor means by means of coupling or hitch members 83 which are carried by the rear end of the frame 15. When it is desired to use the elevator for raising grain or other material, the elevator is raised at one end by operating the power member 47 and shifting one of the gears on the shaft 67 to provide for rotation of winding drum 63 in a winding direction.

Winding of the flexible member 59 on drum 63 will pull the links 57 rearwardly and upwardly so as to thereby raise the forward end of the frame 15. When the elevator is disposed in the desired inclination, shaft 67 is declutched or uncoupled from shaft 41. The material, which may be corn or other grain, is then discharged onto the lower end of the conveyor, and as the corn which is on the cob passes over the screen or

grill 49, the loose corn or other relatively small material will drop through the screen 49. The remaining material will be carried upwardly and discharged from the upper end of the conveyor

5 28. By providing the non-metallic or other runners 26 for the chains 29 on the upper runs of these chains, a substantial amount of noise is eliminated, and in addition the wear on the chains will be very materially reduced.

10 Where the material is relatively small such as small grain or the like, a plate may be disposed over the opening 48 in the trough bottom so that the small material will not drop through the opening 48.

15 This elevator will provide a means whereby grain or other material may be elevated and discharged into an upper storage bin, and where electric power is not available, the power member 47 may be in the form of a small internal combustion engine.

20 What is claimed is:

1. A portable elevator comprising an elongated frame, a pair of endless conveyor chains having upper and lower runs, driving means for said chains carried by said frame, spaced cleats connected between said chains, a wheeled frame, a pair of links pivotally connected between said first frame and said wheeled frame, a second pair of links pivotally connected to said wheeled frame and extending oppositely from said first pair of links, rollers carried by said second pair of links engaging beneath said first frame, and means for moving said second links relative to said first frame to thereby raise or lower the latter, said means comprising a sheave secured to said second links, a pulley connected to the underside of said first mentioned frame, a shaft carried by said first mentioned frame, a flexible member formed about said sheave and pulley and adapted to be secured to said shaft and selectively wound and unwound about said shaft upon rotation thereof to vary the angular relation of said second mentioned link relative to said first mentioned frame, a gear carried by said shaft, a second shaft carried by said frame at right angles to said first mentioned shaft, a worm gear meshing with said first gear carried by said second shaft oppositely disposed spaced bevel gears carried by said second shaft spaced from said worm gear, a driven bevel gear selectively engageable with one of said opposite bevel gears, means for moving said second shaft from central gear disengaged position to selectively engage one of said oppositely disposed bevel gears selectively to rotate said second shaft and hence said first shaft in either of two directions, said last mentioned means including a double collar on said second shaft and a manually operable pivoted shifting fork engaging said collar, and means including a collet secured to said second shaft and a coil spring surrounding said second shaft positioned between said collet and said worm gear whereby said shaft may be moved relative to said worm gear without affecting the driving connection therebetween.

2. A portable elevator comprising an elongated frame, a pair of endless conveyor chains having upper and lower runs, driving means for said chains carried by said frame, spaced cleats connected between said chains, a wheeled frame, a pair of links pivotally connected between said first frame and said wheeled frame, a second pair of links pivotally connected to said wheeled frame and extending oppositely from said first

pair of links, rollers carried by said second pair of links engaging beneath said first frame, and means for moving said second links relative to said first frame to thereby raise or lower the latter, said means comprising a sheave secured to said second links, a pulley connected to the underside of said first mentioned frame, a shaft carried by said first mentioned frame, a flexible member formed about said sheave and pulley and adapted to be secured to said shaft and selectively wound and unwound about said shaft upon rotation thereof to vary the angular relation of said second mentioned link relative to said first mentioned frame, a gear carried by said shaft, a second shaft carried by said frame at right angles to said first mentioned shaft, a worm gear meshing with said first gear carried by said second shaft, oppositely disposed spaced bevel gears carried by said second shaft spaced from said worm gear, a driven bevel gear selectively engageable with one of said opposite bevel gears, and means for moving said second shaft from central gear disengaged position to selectively engage one of said oppositely disposed bevel gears selectively to rotate said second shaft and hence 25

said first shaft in either of two directions, and means including a collet secured to said second shaft and a coil spring connected between said collet and said worm gear whereby said shaft may be moved relative to said worm gear without affecting the driving connection therebetween.

THOMAS RYAN MAHONEY.
